COMBINED FURNACE AND CLOTHES DRYER FOR HOUSE TRAILERS

Arthur F. Habener, 217 E. Water, Anaheim, Calif.

Filed May 18, 1959, Ser. No. 55,933

Term of patent 14 years

(CL. D81—19)

The figure is a front perspective view showing the left side of a combined furnace and clothes dryer for house trailers embodying my new design.

The right side not shown is substantially the same as the left side shown and the rear is substantially plain. The top is plain aside from a conventional flue opening.

I claim:

The ornamental design for a combined furnace and clothes dryer for house trailers, substantially as shown and described.
